US00D992964S

(12) United States Design Patent (10) Patent No.: US D992,964 S
Liu (45) Date of Patent: * Jul. 25, 2023

(54) HANDLE

(71) Applicant: Yangjiang Yangdong Xingtai Hardware Wooden Manufacture LLC., Yangjiang (CN)

(72) Inventor: Guixing Liu, Yangjiang (CN)

(73) Assignee: Yangjiang Yangdong Xingtai Hardware Wooden Manufacture LLC., Yangjiang (CN)

() Term: 15 Years

(21) Appl. No.: 29/790,664

(22) Filed: Dec. 7, 2021

(51) LOC (14) Cl. 07-02

(52) U.S. Cl.

USPC D7/395

(58) Field of Classification Search
